TEXTILE ROPE-STACKING APPARATUS

Sydney Steele, Wilmington, Del., assignor to E. I.
du Pont de Nemours & Company, Wilmington,
Del., a corporation of Delaware

Application March 1, 1945, Serial No. 580,464

3 Claims. (Cl. 28—1)

1

This invention relates to apparatus for the orderly stacking or piling of textile rope in a container.

In the textile arts, it is generally desired to treat textile goods, for example, cloth, fiber bundles, piece goods and the like with solutions such as dyeing, bleaching, scouring or similar solutions to properly prepare the textile goods for merchandising. Frequently, goods treated with solutions are placed in containers for storage to permit the solutions to remain in contact with the goods over extended periods of time, or for purposes of steaming, or otherwise heating goods previously subjected to treating solutions; for example, in the manner disclosed in U. S. Patent to Campbell et al. No. 2,287,718. Textile goods, in the process of treatment, also are frequently passed in a continuous manner through several pieces of equipment, and temporary storage means, referred to in the arts as "slack boxes" or "scrays," are provided between such pieces of equipment.

Such textile goods are commonly formed into ropes or extended bundles which are fed into a storage container, or the like, by means of apparatus comprising a traversing mechanism in combination with a piling or plaiting mechanism; the traversing mechanism functioning to traverse the goods in rope form back and forth from side to side of the container, and the plaiting mechanism functioning to move the goods back and forth from front to back of the container. Such apparatus usually contains a plurality of synchronously moving parts which are subject to wear and loss of timing whereby the apparatus often loses its efficiency, or even its operability, to orderly pile or stack the goods in the container.

It is an object of this invention to provide an improved piling or stacking apparatus for use in the orderly stacking of textile rope in a container.

It is another object of this invention to provide a stacking mechanism for textile rope which mechanism comprises a single moving part.

It is still another object of this invention to provide in a single roller, means for forwarding textile goods and move the same both from side to side, and from front to back of a container.

Other objects of the invention will appear hereinafter.

The objects of the invention may be accomplished, in general, by a reverse helically grooved forwarding roller, in which the bottom of the helical grooves about the roller define a circumferential elliptical outline.

2

The details of the invention will be more clearly apparent by reference to the following description when taken in connection with the accompanying illustrations in which:

Fig. 1 is a perspective view of a reverse helically grooved elliptical roller, constructed in accordance with the present invention, in position above a storage container.

Fig. 2 is a diagrammatic side elevational view of a grooved elliptical roller, in two positions, to illustrate the manner in which it functions to move a rope from front to back of the container.

Fig. 3 is a perspective view of a portion of a modified form of reverse grooved roller constructed in accordance with this invention.

Referring to Fig. 1, reference numeral 8 designates a rope-forwarding roller of elliptical cross-section. Roller 8 is journaled for rotation in the top of a container 10. The roller shaft 12 may be rotated by an electric motor or any other type of driving mechanism (not shown). The roller 8 is provided with reverse helical grooving 14 sufficient depth to traverse a textile rope from side to side of the container 10. The grooves 14 must have a depth of at least $\frac{1}{4}$ inch and the bottom of the helical grooves, taken about the roller 8, must form an elliptical path circumferentially of the roller. If the external surface of the roller 8 is elliptical in cross-section, the grooves 14 may have a substantially uniform depth, as shown in Fig. 1 of the drawing (except for possible slight non-uniformities in depth to prevent slipping of the rope from the groove or grooves as described in U. S. Patents Nos. 1,749,355 and 1,918,210), and thereby providing a helically grooved roller in which the bottom of the grooves form an elliptical path circumferentially of the roller.

The textile rope 16, consisting of continuous cloth goods, fiber bundles, or joined piece goods, is pulled by the roller 8 to forward the same to the container 10. The rope is traversed back and forth from side to side of the container by following the reverse helical groove or grooves of roller 8. Since the bottom of the helical grooves form an elliptical path circumferentially of the roller, the textile rope is also thrown from front to back of the container as it is being traversed from side to side. The rope is thereby piled or stacked in the container in the manner shown. It is, therefore, readily apparent that the single rotating roller 8, helically grooved as above described, is the sole operating member to forward and stack the goods in the container 10 in an orderly manner.

Fig. 2 of the drawing illustrates, diagrammatically,

cally, how the roller 8 of Fig. 1 throws the textile rope from front to back of the container 10. The bottom 18 of the helical grooves of roller 8 are shown as defining an elliptical path circumferentially of the roller. The distance "X" represents the difference, at the forward side of the roller, between the short and long radii of the bottom of the grooves. The rope 16 is stacked from front to back of the container 10, even though the distance "X" is somewhat less than the width of the container, since it is caused to swing by the progressively changing contact of the rope with surfaces of the roller having different radii. In the drawing, the roller 8 is shown positioned, relative to the container 10, to place the distance "X" above the center of the container. Although this centered position of "X" above the container is generally preferred, in some cases the throw is not equal in both directions and, therefore, it may be more desirable to offset "X" from the center line to compensate for the uneven throw.

Figure 3 of the drawing illustrates a modified form of reverse helically grooved roller which is capable of moving a textile rope both from side to side and front to back of a container. Roller 20, as shown in Fig. 3, has a cylindrical outer surface provided with grooves 24 of varying depth so that the bottom of the groove or grooves 24 will again form, about the roller, a circumferential path of elliptical outline, as shown by 22 which constitutes a projection of the bottom outline of the groove upon the face of the roller. A rope-stacking roller of this form will have the advantage that it ensures the maintenance of the rope in the grooves despite the throwing effect of the elliptical bottom of the grooves, since grooves of greater depth are provided at that section of the roller from which the rope would have a tendency to jump the groove.

Round, reverse helically grooved rollers for traversing of textile goods are well known in the art; such rollers being exemplified by U. S. Patents Nos. 1,749,355 and 1,918,210. However, prior to this invention, when used in the traversing of textile goods which were piled or stacked in a container, it was always considered necessary to combine such a helically grooved roller with a plaiting roller to move the goods from front to back of the container, as well as from side to side. This necessitated a plurality of

moving parts, moving synchronously with each other to produce the desired result. By the present invention, the disadvantages entailed by a mechanism comprising a plurality of moving parts are eliminated.

The reverse helical grooving in the rope-forwarding rollers of the present invention may be constructed with any of the many known refinements for preventing the slipping or jumping of the textile rope from the groove or grooves. Since reverse helical grooving in rollers for the purpose of traversing textile rope is generally known, and since the specific construction of the helical grooving does not form a part of the present invention, details relating to specific refinements in the groove construction are generally omitted from the present specification. In order that the reverse helically-grooved rollers of the present invention may apply the desired pull or tension on the textile rope, it may be desired to provide the same with surface characteristics which will impart the desired frictional pull on the textile rope. The surface within the grooves may, for example, be coated with a suitable slightly tacky resin or rubber composition, or it may be slightly roughened by sand-blasting or by spray-coating with molten metal, or the like. The grooves are preferably provided with slightly rounded corners to prevent undue abrading, or even tearing, of the textile goods.

Since it is obvious that many other changes and modifications can be made in the details above described without departing from the nature and spirit of the invention, it is to be understood that the invention is not to be limited except as set forth in the appended claims.

I claim:

1. A textile rope forwarding roller having reverse helical rope-forwarding grooves in which the bottom of the grooves, circumferentially of the roller, form an elliptical outline.
2. A textile rope forwarding roller, elliptical in cross-section, having reverse helical rope-forwarding grooves in which the bottom of the grooves, circumferentially of the roller, form an elliptical outline.
3. A cylindrical textile rope forwarding roller having reverse helical rope-forwarding grooves in which the bottom of the grooves, circumferentially of the roller, form an elliptical outline.

SYDNEY STEELE.
